CLAIM

The ornamental design for a knife, as shown and described.

DESCRIPTION

FIG. 1 is top right perspective view of a knife according to my design;

FIG. 2 is a top left perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front view thereof;

FIG. 8 is a back view thereof;

FIG. 9 is a cross section along the line 9-9 of FIG. 4;

FIG. 10 is a cross section along the line 10-10 of FIG. 3;

FIG. 11 is a detail view of region 11 of FIG. 9; and,

FIG. 12 is a detail view of region 12 of FIG. 9.

The dot-dash broken lines show the extent of the detail views and form no part of the claimed design.
